UNITED STATES PATENT OFFICE.

EDWARD C. GLEDHILL, OF GALION, OHIO.

UNLOADING APPARATUS.

1,230,700.

Specification of Letters Patent. Patented June 19, 1917.

Application filed February 25, 1916. Serial No. 80,422.

To all whom it may concern:

Be it known that I, EDWARD C. GLEDHILL, a citizen of the United States, residing at Galion, in the county of Crawford and State 5 of Ohio, have invented certain new and useful Improvements in Unloading Apparatus, of which the following is a specification.

This invention relates to apparatus for unloading freight cars containing stone, coal, sand, or similar material and transferring the load to a bin from which it may be discharged into wagons or other conveyances to be transported to the place of use. One object of the invention is to provide an apparatus which may be easily installed and another object of the invention is to provide means whereby the bin and the parts immediately coacting therewith may be easily transferred from one point to another so as to permit the unloading of a number of cars successively. A particular object of the invention is to provide means for positively delivering the stone or other material from a point beneath the car to an elevator by 15 which it is transferred to the bin, and another object of the invention is to provide a novel construction whereby the elevator may be brought into a reduced compass to permit the travel of the bin.

All these stated objects and other objects which will incidentally appear are attained in the apparatus illustrated in the accompanying drawings and the invention resides in certain novel features which will be particularly pointed out in the claim following the detailed description.

In the drawings:

Figure 1 is a view partly in elevation and partly in section of the complete apparatus; 40 Fig. 2 is an end view of the elevator;

Fig. 3 is a perspective view of the hopper or receptacle which receives the load from the car;

Fig. 4 is a detail view of a portion of the drag chain or feeder;

Fig. 5 is a detail view of a closure for the receptacle or hopper;

Fig. 6 is a detail perspective view of the feeder which operates in the bottom of the 50 receptacle.

In carrying out my invention, I provide below the track 1 and between the ties by

which said track is supported, a hopper or receptacle 2 which is of such dimensions as to extend entirely across the bed of the track 55 and is adapted to receive the stone or other material from the car. This hopper or receptacle may be of any preferred material and will generally be constructed of metal in order to attain durability. In the top 60 of the receptacle, adjacent and parallel with one side of the same, are a series of openings 3 which are adapted to be closed by doors 4, said doors being hinged at the far sides of the openings and supported by bolts 65 or similar catches 5 at the near sides of the openings. A spring 6 is provided for each door and bears against the under side of the same so as to normally hold the door in its raised closed position. The bolt or catch 70 5 is preferably a sliding bolt connected by a link 7 with a lever 8 pivoted upon the hopper or receptacle and having an operating cable or other medium 9 attached to its free end. The said cable 9 extends to the end 75 of the receptacle where it may be easily grasped by the operator and the several doors are provided with similar levers and operating means so that each door may be opened independently of all the other doors. 80 The bolt may be mounted on the under surface of the top of the receptacle and the pin connecting the link 7 with the lever 8 may extend through a slot in the said top, or any other convenient arrangement may be adopted 85 so as to accommodate the parts and permit them to be operatively connected. The lever 8 may be connected with a spring 10 so that, when the cable 9 is released, the lever will at once return to its normal position and 90 the bolt be carried under the free edge of the door. The spring 6 should be strong enough to support the door in its raised or closed position under normal conditions so that, when the stone or other material ceases 95 to flow, the door will at once return to its closed position so that the door opening will not remain uncovered and persons walking along the track or near the hopper will not be liable to be injured by falling or tripping 100 upon the opening. When the door is in its closed position, the bolt 5 will project under the free end of the door so as to support it against the weight of material thereon until

a pull is exerted upon the cable 9 to retract the bolt. It will thus be seen that the operator may open one or more of the inlets to the hopper or receptacle, according to the direction in which the load is discharging from the car, so that the material will not pass into the hopper too rapidly and exert a strain upon the feeder beyond the capacity of the same.

10 The near end of the receptacle is open, as shown in Fig. 3, and from the bottom of the said receptacle projects a hopper or trough 11 in which the lower bight of the elevator is disposed. In the lower end of the elevator frame is journaled a transverse shaft 13 equipped with a sprocket wheel 14 at one end. A chain 15 is trained around said sprocket and a sprocket 16 on the end of a shaft 17 which is journaled in one side of 15 the receptacle 2 and in a partition 18 within said receptacle, the inner end of said shaft 16 being equipped with a beveled pinion 19, as shown clearly in Fig. 3. This beveled pinion 19 meshes with a beveled gear 20 on 20 a vertical shaft 21 which is journaled in the top and bottom of the receptacle 2. Adjacent the lower end of the said shaft 21 is a sprocket wheel 22 around which is trained a drag chain 23. This drag chain passes also 25 around a sprocket wheel 24 at the lower end of a shaft 25 journaled in the top and bottom of the receptacle and the alternate links of the chain carry outstanding arms 26 which are so disposed as to ride over the 30 bottom of the receptacle and thereby push the stone or other material through the open end of the receptacle into the trough 11. These arms 26 may be of any convenient construction and are illustrated as constructed of stout rods bent substantially into V-form having one side radial to the chain and the other side acting as a brace for the said radial side. The radial side will strike 35 squarely against the material and push the same from the receptacle while the inclined or brace side will aid the said material-engaging side in resisting the bending strain. The construction moreover will permit the arms to spread slightly or yield to the bending or change of position of the chain as it 40 passes around the sprocket wheels. A partition 27 extends longitudinally of the receptacle between the plane of the door openings and the plane of the drag chain so that the 45 material will be prevented from falling over onto and between the runs of the drag chain and thereby clogging the operation of the apparatus.

The elevator is supported from the bin 28 by links or arms 29, 30, 31 which are pivotally attached to the bin and to the elevator frame, as will be readily understood. The elevator frame is constructed in two members or sections connected by a hinge, as in-

dicated at 32, so that it may be readily folded to lie over the bin, as indicated by dotted lines in Fig. 1. A chute 33 is provided at the upper end of the elevator and is supported from the elevator frame by a link or brace 34, as will be readily understood. The elevator is driven by a shaft 35 which is journaled in the sides of the elevator frame and extends across the same between the runs of the apron 36 carrying pockets 37 which constitute the carrying member of the elevator. The said shaft 35 is equipped with a pulley 38 at one end around which is trained a belt 39 which also passes around a pulley 40 on the driving shaft of a motor M mounted upon the lower portion of the bin. The shaft 35 carries a pulley or sprocket wheel 41 at the end opposite the pulley 38 and a chain or cable 43 is trained around the said member 41 and a similar member 43 at the upper end of the elevator. Motion is imparted to the apron from the shaft 44 carrying the pulley or sprocket wheel 43 and the consequent travel of the apron imparts rotation to the shaft 13 which carries the roller 45 around which the lower part of the apron passes. A drum or windlass 46 is mounted upon the bin and equipped with a crank or other handle 47, a cable 48 being wound upon and secured to the said drum and passing therefrom to the elevator to which it is secured near the lower end thereof, as indicated at 49. It will now be readily understood that the elevator is driven from the motor M which may be a gasoline engine or of any other preferred type. If the chain 15 be disconnected and the link 31 released at one end, the cable 48 may be wound upon the windlass 46 and the lower end of the elevator thereby drawn upwardly and inwardly toward the bin, the links 29 and 30 swinging up and over so that the elevator frame may fold upon the hinge 32 and lie close to and upon the bin, as shown by dotted lines in Fig. 1. It is also to be noted that the bin will preferably have its sides constructed in two sections connected by hinges 50 so that the said sides may be folded to accommodate the folded position of the elevator and reduce the height of the structure so that it may be readily moved from one to another point of use. It will also be noted that the bin is mounted upon wheels 51 so that it may be very easily moved from place to place and the usual discharge spout 52 is provided whereby the contents of the bin 55 may be discharged into wagons or other conveyances.

The operation and many advantages of my improved apparatus are thought to be apparent from the foregoing description, taken in connection with the accompanying drawings, and further detailed reference thereto is deemed unnecessary.

Having thus described the invention, what is claimed as new is:

In an apparatus for the purpose set forth, the combination of a portable bin having 5 foldable sides, an elevator swingingly supported from said bin and consisting of sections hinged together at their meeting ends

whereby it may be swung close to and fold over the bin, a drum on the bin, and a cable wound upon the drum and secured to the 10 elevator near the lower end thereof.

In testimony whereof I affix my signature.

EDWARD C. GLEDHILL. [L.S.]
